WRENCH

Lars E. Hagbo, Seattle, Wash.

Application January 16, 1933, Serial No. 651,930

5 Claims. (Cl. 81—143)

My invention relates to wrenches, and includes principles applicable to pipe wrenches as well as to nut wrenches. The present application is a continuation in part of my application Serial No. 5 539,297, filed May 22, 1931, and application Serial No. 36,872, filed August 19, 1935 is a continuation of the instant application.

It is an object of the present invention to provide means whereby a movable jaw of a wrench can be secured in any desired position of adjustment, and further, to provide means whereby the movable jaw can be positively locked in any such position.

It is a further object to provide means of the character indicated above, which can be incorporated in wrenches of the general design now in use, and which can be so located in such wrenches that they will not project especially at the sides, where they may be liable to engage with the work, yet where they are readily accessible by a finger of the hand normally holding the wrench for operation.

It is a further object to provide a wrench of the general character indicated, in which the release of the movable jaw for opening movement under the influence of a spring acting thereon, and the positive locking of the same in any adjusted position, can be accomplished by a single member.

30 It is also an object to provide means of the character indicated which shall be simple in construction and thoroughly reliable in operation, simple to assemble, and by means of which the wrench can be made lighter than wrenches of corresponding type and size now in use.

It is a further object, in conjunction with a pipe wrench particularly, to provide simple and reliable means whereby the movable jaw may always be swung, when not in use, to the position of nearest approach to the fixed jaw, or in an alternative form, to a position intermediate the position of closest approach and the farthest distant position.

It is also an object, in conjunction with a pipe wrench, to construct the same in such manner that the very considerable stresses developed in use can be relieved from the pivot about which the movable jaw swings, and delivered directly from the movable jaw or its immediate support to the handle.

Other objects, and more especially such as pertain to the purely mechanical details of my invention, will be understood from a study of the attached drawings, of this specification, and of the claims.

My invention comprises the novel parts, and the novel combinations and arrangements thereof, as will be seen in the accompanying drawings, described in the specification, and defined by the claims.

In the accompanying drawings I have shown my invention incorporated in various illustrative types of wrenches.

Figure 1 is a side elevation, and Figure 2 an edge elevation of a nut wrench embodying my invention, the handle being omitted.

Figure 3 is a sectional elevation through the same in open position, and Figure 4 is a similar view in the locked operative position.

Figure 5 is a transverse section substantially on the line 5—5 of Figure 4.

Figure 6 is an elevation of my invention incorporated in a pipe wrench, parts being shown in position about to grasp a pipe.

Figure 7 is a sectional elevation of the same wrench with parts locked in position ready to grasp a pipe, and Figure 8 is a similar view with parts in the movable jaw releasing position.

Figure 9 is a transverse section through the same wrench, substantially on the line 9—9 of Figure 7.

Figure 10 is a side elevation, and Figure 11 is an elevation partly in section, showing a slightly modified form of the pipe wrench.

Figure 12 is a sectional elevation of a modified form of the nut wrench.

My invention is incorporated in its simplest form in the nut wrench, which, as shown, is of the well-known crescent type, comprising a handle 10, a fixed jaw 1 formed integral therewith, and a movable jaw 2 formed integral with a slide 20 received within a guide 12 in the head of the wrench, this guide extending perpendicularly to the face of the fixed jaw 1. A spring 21 received upon a pin 11 at one end, and within a cavity 22 in the slide 20 at the other end, is constantly operative to urge the slide and movable jaw away from the fixed jaw, and a cross pin 13 limits such separating movement of the jaws.

Within the head of the wrench, adjacent the guide 12, is a chamber 14 formed in the head of the wrench which may have parallel opposite walls, and one surface at least of this chamber is arranged at an angle to the guide 12, and faces away from the movable jaw 2. Within this chamber is received a slide-engaging member which is shown as the wedge block 3. This wedge block may engage a surface of the slide 20, and by the wedging action of the slide tending to move away from the fixed jaw, in conjunction with the inclined surface of the chamber 14, the slide may be wedged and held in any position, but in order to insure such engagement between the wedge block and slide as will accomplish this result, I prefer that their engaging surfaces be provided with a series of fine, transverse corrugations, as is best illustrated in Figures 3 and 4. Also, to insure engagement of the wedge block with the slide, I provide spring means to urge the wedge block always towards the slide. These

means, as shown, comprise a spring 30 surrounding a pin 31, this pin having a reduced shank 32 and a larger head 33, the head being received in a transverse recess 34 in the wedge block. The 5 spring 30 bears against a button head 35 on the pin 31, and thus urges the wedge into engagement with the slide. The mounting of the head 33 within its recess 34 and of the pin 31 within its recess is such as will permit limited oscillation of the pin 31, and the button 35 is so positioned as to be engageable by the thumb of the hand which normally holds the wrench in operative position.

My invention thus far is identical in principle 15 to that disclosed in my application Serial No. 539,297, the only difference being that in that form, as shown in Figure 12, the wedging member, designated 3" in Figure 12, is substantially triangular in elevation, and instead of the enlarged head 33 there is provided a transverse pin 33' received in a bore in the wedge block 3", and slightly oscillatable therein, the end of the pin 31' being threadedly engaged with the cross pin 33', as indicated at 34'.

20 Referring again to Figures 1 to 5 inclusive, a knurled jaw locking member 4 is provided in position to engage the wedge block 3. This is shown as a nearly circular cam member pivotally mounted at 40 in the head of the wrench. When 25 the locking member 4 is in the position shown in Figures 1 and 3, its flat surface 41 is disposed toward the end of the wedge block 3, and the latter is free to be pushed from engagement with the slide, as is shown in Figure 3. Release of 30 pressure from the button 35, however, will permit the wedge block to return, under the influence of the spring 30, into engagement with the slide 20, and parts are shown in this position in Figure 1. In the position shown in Figure 4, however, the 35 high point 42 of the cam has been turned into engagement with the end of the wedge block 3, and since the wedge block is maintained in engagement with the slide 20 by means of the spring 30, the locking member when swung into 40 this position will positively lock the wedge block 45 and prevent its being pushed from engagement with the slide; consequently the slide is positively locked in any position to which it has been adjusted.

50 It will be noted that the locking member 4 is disposed in an edge of the wrench, not in the side face thereof, and in this position does not project where it is likely to be engaged with the work, consequently it is not likely to be accidentally released, and the workman may proceed with his work with the assurance that the jaws of the wrench are positively locked in whatever position they may have been adjusted. Also, as shown, a spring surrounding the pivot 40 may engage the head or casing and the locking member to frictionally hold such member in an adjusted position. Still, whenever adjustment is required, pressure of a finger releases the locking member, another finger releases the wedge, and the jaw 2 slides fully open under the influence of spring 21. From this position it is simple to move it to the new operative position, and again to lock it.

55 In the pipe wrench, shown in Figures 6 to 9 inclusive, an extra part, the saddle 5, is pivotally supported at 51 from the handle 1, and therefore is not directly connected to the fixed jaw 1, but it is to all intents and purposes a part of the head of the wrench, even though it is a part which is 60 pivotally supported with respect to the handle of

the wrench. The guide 12 is formed in this saddle 5, and the slide 20 is slideable therein under the influence of the spring 21 as before. Movement of the slide in this instance is limited by means of a pin 23 in the slide, engageable within a groove 15 of the handle, and it will be noted that in the full open position of the movable jaw the pin 23 is directly over the axis of the pivot 51, whereby the rocking movement of the movable jaw relative to the handle 10 is not disturbed.

55 In this pipe wrench the engaging or wedging member 3' is urged toward the slide 20 by a spring 30' backed by a removable plug 36. The locking member 4' is received in this instance within a slot 37, formed directly in one side of the wedging member 3', and the point 42', as before, engages a shoulder on the wedging member 3' to hold it in slide-secured position, as illustrated in Figure 7. However, the locking member is provided with an additional point 43 engageable with an end of the slot 37, whereby upon movement of the locking member 4' in a direction opposite to that required to lock the wedging member the latter is moved away from engagement with the slide 20, as may be seen in Figure 8. Thus the locking member in this form performs the dual functions of locking parts in adjusted position and of releasing them from engagement to permit the movable jaw to slide to the extreme outer limits of its movement, and it is shown in this position in Figure 8.

60 It is desirable, in wrenches of this type, to provide spring means to hold the jaws swung somewhat away from their position of farthest approach (usually to the position of nearest approach), in order the more easily to close down upon a pipe. The means which I have provided for this purpose are valuable in connection with this particular type of jaw adjusting and locking means, and are valuable also in conjunction with any type of pipe wrench. For this purpose I provide in the handle 10 a slot 16 extending substantially longitudinally of the handle (but not in line with the pivot 51), and in this slot is received a block 6. By means of a pin 60, or any like means, this block is connected to a depending ear 50 of the saddle 5, the pin 60 passing through a transverse slot 56 in the ear 50 to limit relative movement of the saddle and the handle. The slot 56 is arranged at an angle less than a right angle to a line joining the axes of the pivot pin 51 and the stop pin 60. Consequently the action of a small spring 61 on the lock 6 in effect causes the pin 60, working within the slot 56, to slide to the position farthest distant from the pivot pin 51, or into the position shown in Figure 8, where the movable jaw 2 has been swung about the pivot 51 to the position of closest approach to the fixed jaw 1, engagement of the saddle and jaw 1 limiting this movement. To engage the wrench with a pipe it is a simple matter to depress the end of the saddle 5 or of the slide 20 with the thumb, and thus to swing the wrench open into the position shown in Figure 7, but upon release, the spring 61 again urges the jaws to swing towards each other.

65 In some wrenches means are provided for swinging the movable jaw somewhat away from the position of closest approach, and of maintaining it in a position intermediate that of closest approach of the two jaws and farthest separation of such jaws. I have provided means whereby this result can be accomplished in the modification shown in Figures 10 and 11. In 70 75

this form the slot 56', corresponding to the slot 56 and receiving the ends of the pin 60, has two branches; that is to say, its opposite ends are disposed at an angle to each other, and each of them is at an angle less than 90° to a line joining the axes of the pins 60 and 51. When parts are in the position shown in Figure 11, the spring 61 tends to urge the pin along the slot 56' to a position farthest distant from the pin 51, and it would be urged towards the same position if the pin 60 were in the opposite end of the slot 56'. The result is that parts tend to remain in an intermediate position, as shown in Figure 10, with the jaws partly swung open.

15 In this form (as indeed I might in the preceding form) I have shown the block 6 as so proportioned, relative to its slot 16, and relative to the slot 56', that upon swinging of the movable jaw into the position of closest approach to the fixed jaw, the block 6 bears at the end of its slot 16, and serves, through the pin 60 rather than through the pin 51, to take the longitudinal stresses. Further to strengthen the wrench, in this form as well as in the form just previously described, the pivot ear 52 of the saddle is so formed that it bears snugly against the projecting rear side of the fixed jaw 1, and this engagement, when the parts are in the operative position of Figure 11, is such that the bearing at 25 53 serves as a fulcrum, thus relieving the pin 51 of that duty to a large extent, and considerably strengthening the wrench.

30 It will be observed further that there is no looseness of the slide 20 relative to the saddle 5, and all strains tending to bend the slide are resisted by the long bearing of the same within the saddle, even in the most extended position of parts, as shown in Figures 8 and 11. By the arrangement shown and described, the wrench 35 may be made lighter in weight than wrenches of corresponding type and size now in use, partly because of the elimination of large nuts and the like, and partly because of the fact that the parts may be more closely fitted in place, and thereby made to support each other better, though of lighter material.

What I claim as my invention is:

1. In a wrench, a head including a fixed jaw, said head having a guide extending generally perpendicular to the fixed jaw, a movable jaw having a slide received in said guide, spring means urging the movable jaw away from the fixed jaw, wedging means to secure the slide relative to the head, a spring-held button in the head, positioned for engagement by the thumb of the hand normally holding the wrench, operatively connected to the wedging means to release it, and means engageable with the wedging means when in slide-secured position to positively lock it in such position.

2. In a wrench, a head including a fixed jaw, said head having a guide extending generally perpendicular to the fixed jaw, and an interior chamber one surface of which is disposed facing the jaw and angularly relative to the guide, a movable jaw having a slide received in said guide, spring means urging the movable jaw and slide away from the fixed jaw and towards the angularly disposed surface, a wedge block disposed in the angle between said surface and the slide, the adjoining faces of the slide and wedge block having a plurality of fine corrugations extending transversely of the direction of movement of the slide, by the interengagement of which the wedge block, under the influence of the spring means,

is forced into engagement with the angled surface to lock the slide against movement away from the fixed jaw, a bolt oscillatably received in the wedge block, the head being bored to permit projection of said bolt in a direction substantially parallel to the guide, to a position for engagement by the thumb of a hand normally grasping the wrench, to release the wedge block.

3. In a wrench, a head including a fixed jaw, said head having a guide extending generally perpendicular to the fixed jaw and a surface disposed facing the jaw and angularly relative to the guide, a movable jaw having a slide received in said guide, spring means urging the movable jaw and slide away from the fixed jaw and towards the angularly disposed surface, a wedge block disposed in the angle between said surface and the slide, the adjoining faces of the slide and wedge block having a plurality of fine corrugations extending transversely of the direction of movement of the slide, by the interengagement of which the wedge block, under the influence of the spring means, is forced into engagement with the angled surface to lock the slide against movement away from the fixed jaw, a bolt received in the wedge block, and secured therein by means slightly oscillatable in said wedge block, the head being bored to permit projection of said bolt in a direction substantially parallel to the guide, to a position for engagement by the thumb of a hand normally grasping the wrench, to release the wedge block, and a spring interposed between the head of said bolt and the wrench head, tending to hold the wedge block in the angle between the angled surface and the slide.

4. In a wrench, a head including a fixed jaw, said head having a guide extending generally perpendicular to the fixed jaw and a surface disposed facing the jaw and angularly relative to the guide, a movable jaw having a slide received in said guide, spring means urging the movable jaw and slide away from the fixed jaw and towards the angularly disposed surface, a wedge block disposed in the angle between said surface and the slide, the adjoining faces of the slide and wedge block having a plurality of fine corrugations extending transversely of the direction of movement of the slide, by the interengagement of which the wedge block, under the influence of the spring means, is forced into engagement with the angled surface to lock the slide against movement away from the fixed jaw, a pin received in the wedge block to oscillate upon an axis parallel to the angled surface, a bolt received in said pin, the wedge block and wrench head being bored to permit projection and limited oscillation of the bolt, whereby pressure upon the bolt will release the wedge block.

5. In a wrench, in combination with a head including a fixed jaw, and a movable jaw adapted for motion towards or away from said fixed jaw, a slide integral with said movable jaw, and guided in said head, said head having an interior chamber, means to hold said movable jaw in any desired position comprising a wedge received in said chamber and engageable between the slide and wrench body, means to vary the position of said wedge comprising a bolt connected to said wedge by means slightly oscillatable with respect to said wedge, said bolt extending from the wedge to the surface of the head, and means engageable at will with the wedge to positively lock the same in slide-secured position.
